(57) CLAIM

The ornamental design for a ghost-shaped drinking fountain, as shown and described.

DESCRIPTION

FIG. 1 is a front, right, and top perspective view of a ghost-shaped drinking fountain;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a front, left, and bottom perspective view thereof. The broken lines shown in the drawings depict portions of the ghost-shaped drinking fountain that form no part of the claimed design.

1 Claim, 8 Drawing Sheets
